UNITED STATES PATENT OFFICE.

ARTHUR R. BULLOCK, OF CLEVELAND, OHIO, ASSIGNOR TO THEODORE T. JENNE, OF CLEVELAND, OHIO.

TANK FOR THE DISTRIBUTION AND STORAGE OF GASES.

1,095,993.

Specification of Letters Patent.

Patented May 5, 1914.

Application filed January 15, 1909. Serial No. 472,423.

To all whom it may concern:

Be it known that I, ARTHUR R. BULLOCK, a citizen of the United States, residing at Cleveland, in the county of Cuyahoga and 5 State of Ohio, have invented a certain new and useful Improvement in Tanks for the Distribution and Storage of Gases, of which the following is a full, clear, and exact description, reference being had to the accompanying drawings.

My invention relates to tanks for the storage and distribution of gases, particularly acetylene in a liquid solvent therefor, and has for its object to provide, in a simple, effective and economical manner, a construction of tank wherein the gas and solvent may be stored and from which the gas may be distributed to the burners or other points of use without the liability of agitating the contents thereof, whereby the discharge of the gas from the solvent may proceed uniformly and whereby the access of the solvent to the gas-outlet pipe will be prevented.

20 The invention, broadly stated, consists in a tank having a suitable outlet for the acetylene liberated from its solvent, with a baffle device or interrupter which prevents the bodily movement of the solvent and the consequent uneven and un-uniform liberation of the gas therefrom and the access of the solvent to the outlet pipe.

Generally speaking, the invention may be defined as consisting of the combinations of 35 elements embodied in the claims hereto annexed and illustrated in the drawings forming a part hereof, wherein—

Figure 1 represents a longitudinal sectional view of a tank having my invention applied thereto; and Fig. 2 represents a transverse sectional view on the correspondingly numbered line of Fig. 1.

Describing the parts by reference characters, 1 represents a tank constructed in accordance with my invention, said tank being provided at its opposite ends with heads 2 and 3 respectively, the head 3 being provided with a central recess 4 for the reception of a pressure gage 5 which communicates with the interior of the tank. This tank is filled with acetylene gas and its solvent (preferably acetone) and is provided with an outlet pipe 6 which is secured to head 2 and projects from said head substantially to the longitudinal center of the

tank, being located in proximity to and extending parallel with the upper surface or wall of said tank. Pipe 6 is provided with a controlling valve 7 of any approved construction.

For the purpose of preventing the bodily movement of the solvent within the tank, I provide said tank with an interrupter or baffle device, said device consisting of a series of transverse disks 11, said series 60 extending from end to end of the tank and each disk being substantially coextensive in area with the transverse internal area of the tank. Each disk is provided with a circular flange 12 at the outer edge 65 thereof, which serves two functions, namely, to engage and form a bearing with the inner wall of the tank and to space one disk from another. As will appear from Figs. 1 and 2, each disk is provided with an 70 aperture 13 adjacent to the periphery thereof, the aperture in each disk being diametrically opposite the apertures in its adjacent disks. This arrangement divides the liquid solvent into a comparatively large 75 number of separate bodies, each body being, for the purpose of my invention, independent of the other, whereby the movement of the body of liquid as a whole is prevented. At the right hand end of the tank (which 80 is the end whereinto the pipe 6 projects,) each disk is provided with an aperture near the upper periphery thereof for the reception of said pipe, but with this arrangement the disks having apertures near the 85 lower periphery thereof fit comparatively closely around the pipe 6, while those which have no apertures near the lower periphery are provided with larger openings, whereby the effective area of an upper aperture in 90 each of the latter disks is substantially equal to the area of an upper aperture in any of the disks at the left hand end of the tank and to a lower aperture in any of said disks.

By the construction herein described, it 100 will be apparent that I have provided a receptacle wherein a gas in solution may be conveniently stored and transported without impairing the efficiency of such tank in operation and that I have accomplished the 105 result in a particularly simple and effective manner.

As a summary, it may be said that in my invention disclosed herein there is provided for the tank a baffle device comprising a plu- 110

rality of communicating chambers which are arranged to subdivide the liquid solvent into a number of practically separate bodies. And furthermore, by the construction I have adopted, that is, forming the walls of the baffle very close together, there are three important advantages and results obtained: First, as before pointed out, the solvent liquid contained in the tank is divided into a large number of practically isolated bodies, which reduces the movement of the liquid in the tank to practically nothing. Second, should an explosion take place in any one of the isolated bodies of liquid, the propagation of that explosion to the other bodies would be prevented. Third, the liquid used as a solvent is so spread out over the surface of the baffle that the rapidity of absorption of the gas by the solvent is greatly increased.

Having thus described my invention, I claim:

1. An apparatus for storing gas consisting of a receptacle having therein a plurality of partitions arranged parallel to each other, the said partitions being spaced a slight distance apart, the spaces between the said partitions communicating with each other whereby a series of communicating chambers of small capacity are formed.

2. An apparatus for storing gas consisting of a receptacle having therein a plurality of transverse baffles spaced apart and provided with openings and forming a plurality of communicating compartments, and an outlet pipe communicating with the upper portion of said receptacles, substantially as specified.

3. An apparatus for storing gas consisting of a receptacle having therein a baffle device consisting of a plurality of transverse disks or plates each provided with a laterally-extending spacing projection adapted to engage its adjacent disk or plates,

said plates being provided with openings, the openings in adjacent plates being out of alignment and an outlet pipe extending from said receptacle, substantially as specified.

4. An apparatus for storing gas consisting of a longitudinally-extending receptacle having therein a baffle device, said device consisting of a plurality of transverse plates or disks each being of substantially the transverse area of said receptacle, each plate or disk having a peripheral flange projecting laterally therefrom and an aperture therethrough, and an outlet pipe communicating with said receptacle, substantially as specified.

5. An apparatus for storing gas consisting of a longitudinally-extending receptacle having therein a baffle device, said device consisting of a plurality of transverse plates or disks, said plates or disks each having an aperture therethrough, the apertures in adjacent disks or plates being out of alignment, and an outlet pipe communicating with said receptacle, substantially as specified.

6. An apparatus for storing gas consisting of a longitudinally-extending receptacle having a baffle device therein, said device consisting of a plurality of transverse plates or disks dividing the receptacle into corresponding transverse compartments, an outlet pipe projecting into said receptacle substantially parallel with and adjacent to the upper surface thereof, said plates or disks being each provided with an aperture, some of the disks or plates having aligned apertures for the reception of said pipe, substantially as specified.

In testimony whereof, I hereunto affix my signature in the presence of two witnesses.

ARTHUR R. BULLOCK.
